ALEXANDER KÁLMÁN, OF NEW YORK, N. Y.

MATRIX FOR LINOTYPE-MACHINES.

1,211,946.

Specification of Letters Patent. Patented Jan. 9, 1917.

Application filed August 10, 1916. Serial No. 114,166.

To all whom it may concern:

Be it known that I, ALEXANDER KÁLMÁN, a subject of the King of Hungary, and a resident of the city of New York, in the county of New York and State of New York, have invented certain new and useful Improvements in Matrices for Linotype-Machines, of which the following is a specification.

- 10 The present invention relates to matrices for composing machines, more particularly to matrices for casting machines which cast a line bar, or linotype, from a plurality of assembled matrices.
- 15 The main object of the present invention is to produce a matrix that is provided upon both of its edges with characters or matrices proper, which stand in the same relation to a single distributing device thereon, thereby permitting castings to be made from each edge thereof, and reducing, as will hereinafter appear, to one-half the number of type sets and magazines to be held in stock by the composer.
- 25 With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a perspective view of a matrix constructed in accordance with the principles of this invention; Fig. 2 is a front elevation thereof; Fig. 3 is a section taken on line 3—3 of Fig. 2; Fig. 4 is a side elevation of the same looking in the direction of the arrow marked 4; and Fig. 5 is a side elevation thereof looking in the direction of the arrow marked 5.

The matrix comprises a thin plate 10, of brass or similar material, having in its edge 11 two characters or matrices proper 12, which may be of the same font but of different face, and upon its edge 13 two characters 14 which are of another font and also of

different faces. On both edges the characters stand in the same relation to a distributing device 15; more particularly they are inverted in relation thereto, as usual in the ordinary one-edge matrices heretofore generally in use. The distributing device is formed by providing in the upper end and both faces 16 of the matrix rounded recesses 17, leaving a ledge 18, into which is cut a V-shaped notch 19. This notch has in its two sides teeth 20, which coöperate with a distributor rail or equivalent device in the well-known manner. Attention is called to the fact that the ledge 18 is disposed centrally in relation to the faces 16 of the plate 10. In the lower end of the matrix plate are formed two notches 10' and 10'', their distance from the respective edges of the matrix plate depending upon the size of the type, as usual in these devices, the notch 10' being associated with the edge 11, and the notch 10'' with the edge 13 of the matrix. Matrix shoulders 21 are formed upon both edges 11 and 13 on the plate 10, each edge being provided with two shoulders, one of which is disposed at or near the upper end and the other one at or near the lower end of the edge. These shoulders coöperate with suitably spaced parts, either stationary or movable, on the line handling mechanism, to accurately position and aline the matrices in casting position. The shoulders are disposed, as the ledge 18, centrally upon the edges 11 and 13 in relation to the faces 16 of the plate. In one edge of the matrix, for instance in the edge 11, is between the two characters 12 formed a mark 22, for a purpose hereinafter to be described.

The operation of this device is as follows: The assorted molds are arranged in a magazine with their edges 11 facing in the proper direction, if letters are to be cast from the characters 12 on said edge. The magazine is then put upon the type-setting machine, and the latter actuated in the usual manner to cause the matrices to assemble in a line in their proper order for casting. After a line has been formed, the marks 22 will be arranged in a horizontal line, indicating that all matrices, forming the line, are of the proper font and face. A line mold and a melting pot are then brought into proper relation to the assembled line of letter molds and a cast is taken. If it is intended to use the characters on the edges 13 of the matrices, the latter are removed from the maga-

zine and inverted so that their edges 13 are in proper relation to the magazine.

It is to be observed that the matrix herein described can be used on linotype machines 5 now generally in use without reconstructing any one of the elements or set of elements of the linotype machines.

The ledge 18 and the shoulders 21 are arranged centrally upon the matrix to properly 10 balance the same as they travel with either edge facing the operator on the distributor rail, that is to say, to permit them to travel in vertical positions without tilting or swinging motion on the rail. The notches 10' and 15 10" control the distribution of the matrices according to the size of the letters thereon. There are two notches provided in the matrix herein described, the notch 10' co-acting 20 with the edge 11 thereof and with a stud on the distributing box, and the notch 10" co-acting with the edge 13 of the matrix and with the same stud when the matrix is used in its inverted position.

From the foregoing it appears that a matrix 25 has been provided, from each edge of which a plurality of characters may be cast, and that only one-half the number of type sets and magazines are to be held in stock by the composer compared with the one-edge 30 matrices now in use. By producing a matrix of this type, the handling thereof is greatly facilitated. For instance, the matrices can be run into line with either edge in operative relation to the mold or casting devices, 35 in contra-distinction to the one-edge matrices, which if inverted in the assembling elevator, due to some mistake or trouble on the machine, will not present the proper edge to the casting devices. Furthermore, the 40 modified matrix can be picked up indiscriminately and placed upon the distributor rail, while the one-edged matrices have to be examined carefully in order to bring them into proper position on said rail.

If the characters on one edge of the matrix 45 should become worn and inoperative, this edge is marked conspicuously to caution the typesetter, and the matrix is then placed into the magazine with its intact edge in 50 proper relation to the setting mechanism.

What I claim is:

1. A linotype matrix having on both edges thereof characters standing in the same direction, and a distributing device and alining 55 means both of which are disposed centrally

in relation to the opposite faces of the matrix.

2. A linotype matrix having a single distributing device and characters on both edges thereof inverted in relation to said distributing device, and alining means disposed centrally in relation to the opposite faces of the matrix, said distributing device being also arranged centrally in relation to the opposite faces of the matrix. 60

3. A linotype matrix having a distributing device and alining means both of which are disposed centrally in relation to the opposite faces thereof. 65

4. A linotype matrix having on both edges 70 thereof characters standing in the same direction, and a distributing device and alining means disposed centrally in relation to the opposite faces thereof, said matrix having in its lower end two font distinguishing 75 notches, each coöperating with one of the edges thereof.

5. A linotype matrix having a single distributing device and characters on both edges 80 thereof standing in the same relation to said distributing device, and alining means upon said edges disposed centrally in relation to the opposite faces of the matrix, said matrix having in its lower end two font distinguishing notches, each coöperating 85 with one of the edges thereof.

6. A linotype matrix having a single distributing device and characters on both edges 90 thereof inverted in relation to said distributing device, and alining means disposed centrally in relation to the opposite faces of the matrix, said matrix having in its lower end two font distinguishing notches, each coöperating 95 with one of the edges thereof.

7. A linotype matrix having a single distributing device and characters on both edges 95 thereof inverted in relation to said distributing device, and alining means disposed centrally in relation to the opposite faces of the matrix, said distributing device 100 being also arranged centrally in relation to the opposite faces of the matrix, said matrix having in its lower end two font distinguishing notches, each coöperating with one of the edges thereof. 105

Signed at New York, in the county of New York, and State of New York, this 4th day of August A. D. 1916.

ALEXANDER KÁLMÁN.
